(57) **CLAIM**

The ornamental design for a bracket, as shown and described.

DESCRIPTION

FIG. 1 is a rear perspective view of a bracket showing my new design according to one implementation.

FIG. 2 is a front perspective view of the bracket in FIG. 1.

FIG. 3 is a rear view of the bracket in FIG. 1.

FIG. 4 is a front view of the bracket in FIG. 1.

FIG. 5 is a left side view of the bracket in FIG. 1. The right side view of the bracket in FIG. 1 is a mirror image of the left side view.

FIG. 6 is a top view of the bracket in FIG. 1.

FIG. 7 is a bottom view of the bracket in FIG. 1.

FIG. 8 is a rear perspective view of the bracket according to another implementation.

FIG. 9 is a front perspective view of the bracket in FIG. 8.

FIG. 10 is a rear view of the bracket in FIG. 8.

FIG. 11 is a front view of the bracket in FIG. 8.

FIG. 12 is a right side view of the bracket in FIG. 8. The left side view of the bracket in FIG. 8 is a mirror image of the right side view.

FIG. 13 is a top view of the bracket in FIG. 8.

FIG. 14 is a bottom view of the bracket in FIG. 8.

FIG. 15 is a rear perspective view of the bracket according to yet another implementation.

FIG. 16 is a front perspective view of the bracket in FIG. 15.

FIG. 17 is a rear view of the bracket in FIG. 15.

FIG. 18 is a front view of the bracket in FIG. 15.

FIG. 19 is a left side view of the bracket in FIG. 15. The right side view of the bracket in FIG. 15 is a mirror image of the left side view.

FIG. 20 is a top view of the bracket in FIG. 15.

FIG. 21 is a bottom view of the bracket in FIG. 15.

FIG. 22 is a rear perspective view of the bracket according to another implementation.

FIG. 23 is a front perspective view of the bracket in FIG. 22.

FIG. 24 is a rear view of the bracket in FIG. 22.

(Continued)

FIG. 25 is a front view of the bracket in FIG. 22. FIG. 26 is a left side view of the bracket in FIG. 22. The right side view of the bracket in FIG. 22 is a mirror image of the left side view. FIG. 27 is a top view of the bracket in FIG. 22; and, FIG. 28 is a bottom view of the bracket in FIG. 22. The broken lines, showing the remaining portions of the bracket and its environment, form no part of the claimed design.

1 Claim, 24 Drawing Sheets
